UNITED STATES PATENT OFFICE.

ULRUS H. MCNEIL AND FRANCIS G. PEARCE, OF WOODS CROSS, UTAH.

LOUD SPEAKER.

Application filed January 15, 1927. Serial No. 161,316.

Our invention relates to radio reception and has for its object to provide a new and efficient loud speaker for radios.

A further object is to provide an economically constructed loud speaker for radios which has few parts and is easily and economically constructed and assembled and one in which the parts may all be made with few operations.

10 A further object is to provide a radio loud speaker which will eliminate much of the static now found in most loud speakers and much of the vibration from the working parts of the speaker.

15 These objects we accomplish with the device illustrated in the accompanying drawings in which similar numerals and letters of reference indicate like parts throughout the several views and as described in the 20 specification forming a part of this application and pointed out in the appended claims.

In the drawings in which we have shown the best and most preferred manner of building our invention, Figure 1 is a plan view 25 of the loud speaker. Figure 2 is a plan view of the same with parts removed. Figure 3 is a side elevation of the device with the coils removed from their cores. Figure 4 is a plan view with only the pole pieces shown attached to the base. Figure 5 is a diagrammatic view of the coils and armature showing the way that the armature is suspended and the connection of the armature with the diaphragm.

30 In the drawings we have shown the base, in which the diaphragm A is mounted as B. Two pole pieces 1 and 2 stamped from soft iron are riveted to the said base B, as shown in Figure 4, with the bolts 3 and 4 shown protruding therefrom. The said bolts 3 and 4 are passed through the base B and the pole pieces 1 and 2 and hold the entire assembly together. A non-conductor plate 5, having 35 holes therethrough to match the bolts, is then placed on the bolts 3 and 4, with an insulator plate D superimposed thereon, and the free ends of a permanent magnet C are placed under the said plate 5 and held in place by screwing the nuts 6 down on the bolts 3 and 4, with the ends of the magnet clamped under the ends of the plate 5 and on top of the pole pieces 1 and 2. Connection terminals 7 are secured to the said insulator plate D and are adapted to be connected with the radio set, and are also connected with the electromagnets E. The said

electromagnets E are carried on soft iron cores 8 and 9 which cores are secured on the ends of the pole pieces 1 and 2, as shown in Figure 3. The said electromagnets are connected with the terminals 7 by the wires 10 and 11. An armature F is mounted above the said electromagnets by being suspended from the non-conductor plate 5 by two spaced apart suspension pins 12 and 13, and one end of the said armature is tapered to a point and is connected with the diaphragm A by a pin 14.

The operation of our device is as follows: When the loud speaker is assembled and connected with a receiving set it is ready to operate and the pulsations of the incoming electrical circuits will act upon the electromagnets and will vibrate the armature F which will, in turn, through the pin 14, 75 transmit the vibrations to the diaphragm A and will reproduce the music, voice or code being sent over the air or wires.

The suspension of the diaphragm over the electromagnet cores gives a clear, decided action to the armature, and transmits that to the diaphragm, thus giving clearer reception. The pole pieces 1 and 2 are stamped out of sheet metal and are identical in form and all of the parts of the entire assembly 85 are easily and cheaply built.

Having thus described our invention we desire to secure by Letters Patent and claim:—

1. In a loud speaker the combination of a 90 base, having a diaphragm mounted therein; pole pieces riveted to said base; a permanent magnet superimposed over said pole pieces and held in contact therewith by bolts; bolts secured in said base and passed 95 through said pole pieces and on which nuts are provided to hold the entire assembly together; a non-conductor plate over the ends of said magnet and holding said magnet to said pole pieces by the pressure exerted 100 by the bolts and nuts thereon and therethrough; cores secured on said pole pieces and carrying electromagnets; an armature suspended from said non-conductor by spaced apart pins and said armature held 105 directly over said electromagnets; and a pin connecting said armature with said diaphragm.

2. In a loud speaker the combination of a 110 base; a diaphragm mounted in said base; pole pieces secured on said base; a permanent magnet superimposed over said pole

pieces; bolts secured in said base; a non-conductor plate over the ends of said permanent magnet adapted to be drawn down on said magnet by said bolts to hold said magnet in fixed relation to said pole pieces and said base; cores of soft iron secured in the ends of said pole pieces; electromagnets carried on said cores; an armature suspended from said non-conductor plate by spaced

apart pins, suspending said armature over **10** the said cores and electromagnets; a pin connecting one end of said armature with said diaphragm; and nuts on said bolts to hold the entire assembly together.

In testimony whereof we have affixed our signatures.

ULRUS H. McNEIL.
FRANCIS G. PEARCE.
